[57] CLAIM

The ornamental design for a combined bottle cap and capsule piercing device, substantially as shown and described.

DESCRIPTION

FIG. 1 is a bottom perspective view of a combined bottle cap and capsule piercing device;

FIG. 2 is a bottom plan view;

FIG. 3 is a side elevational view in an upside down position;

FIG. 4 is a medial sectional view taken through FIG. 3;
and

FIG. 5 is a top plan view thereof.
